(57) **CLAIM**

The ornamental design for a charging station, as shown and described.

DESCRIPTION

FIG. 1 is a perspective view showing the new design for a charging station;

FIG. 2 is a front view thereof;

FIG. 3 is a top view thereof;

FIG. 4 is a rear view thereof;

FIG. 5 is a left side view thereof, the right side being a mirror image thereof;

FIG. 6 is a bottom view thereof; and,

FIG. 7 is a perspective view of another charging station showing the new design.

The claimed design is not limited to specific colors or materials. A first embodiment of the claimed design illustrated in FIG. 1, for example, comprises an opaque material. A second embodiment of the claimed design illustrated in FIG. 7 comprises a transparent or translucent material as indicated by oblique line shading.
